UNITED STATES PATENT OFFICE.

OWEN OSBORNE, OF PHILADELPHIA, PENNSYLVANIA.

CUT STOCKING.

SPECIFICATION forming part of Letters Patent No. 288,592, dated November 13, 1883.

Application filed June 6, 1883. (Model.)

To all whom it may concern:

Be it known that I, OWEN OSBORNE, a citizen of the United States, and a resident of Philadelphia, Pennsylvania, have invented 5 certain Improvements in the Manufacture of Cut Stockings, of which the following is a specification.

One object of my invention is to prevent waste in the manufacture of cut stockings, and 10 a further object is to improve the appearance of stockings made from tubes of knitted fabric. These objects I attain in the manner which I will now proceed to describe, reference being had to the accompanying drawings, in which—

15 Figure 1 is a view of part of a stocking made according to my invention; Fig. 2, a view showing the ordinary method of cutting a knitted tube in order to produce such a stocking, and showing the waste caused thereby; Fig. 3, 20 a diagram showing why this method of cutting is adopted; Fig. 4, a diagram illustrating my improved method of cutting the stockings, and Fig. 5 a view showing another plan of carrying out this feature of my invention.

25 In making cut stockings with a barred toe, such as shown in Fig. 1, great waste is caused, owing to the fact that when the tube is made with continuous transverse stripes, as usual, it is impossible to alternate the tongues for forming the feet, as is done in making plain stockings. Thus, on reference to Fig. 3, it will be observed that when the tube is cut on the lines x and y to form the tongues a and a' on the stockings A and A' , respectively, the bands b 30 are equidistant from the center of the tongue a , and hence are adapted to form a barred toe when said tongue is folded on the central line, d ; but the bands b on the tongue a' are not in the center of the tongue, and hence cannot 35 form a barred toe on the foot made by folding the latter. For this reason the plan shown in Fig. 2 has been generally adopted in making stockings of this class, the tongues a and a' being alternated, as shown, and the shaded portions 40 f being wasted. To overcome this objection, and produce a stocking with barred toe by the

usual method of cutting, without waste, I form in the knotted tube, at the proper intervals, stripes running but half-way around the tube. Thus, as shown in Fig. 4, a half-stripe, b' , is 50 arranged at an equal distance on each side of the continuous stripe b , one stripe, b' , being on one half of the tube and the other on the opposite half. When this tube is cut, and each tongue a and a' folded on the central line, d , each 55 half-stripe b' will coincide with half of the stripe b , and the desired barred toe will be produced. The same result may be attained by arranging the half-stripes in the manner shown in Fig. 5; but the plan shown in Fig. 4 is simpler, and is preferred.

The half-stripes impart a more attractive appearance to the leg of the stocking than stripes extending completely around the tube, and hence are of value in this respect, independently of the saving effected in cutting the blanks from the tube. The half-stripes are produced by feeding in a different thread for a half-turn of the needle-cylinder, in a manner readily understood by those familiar with knitting operations.

I claim as my invention—

1. The mode described of forming, without waste, cut stockings having feet with barred toes, said mode consisting in knitting the tube 75 with opposite half-stripes, cutting the tube to form projecting tongues, and folding said tongues, whereby the half-stripes are caused to coincide and form the barred toe, as set forth.

2. A knitted tube having transverse stripes 80 extending only part way around the same, said tube being adapted to be cut and folded so that the half-stripes will coincide with each other, as set forth.

In testimony whereof I have signed my name 85 to this specification in the presence of two subscribing witnesses.

OWEN OSBORNE.
